GARMENT SUPPORTING STRAP

Sally Ann Siegel, Los Angeles, Calif.

Application April 9, 1954, Serial No. 422,011

2 Claims. (Cl. 2—338)

My invention has to do with shoulder straps for supporting garments from the shoulders of a wearer.

While my improved shoulder strap is particularly useful to support brassieres, it is also useful for supporting other garments such as slips, dresses, bathing suits, etc.

A disadvantage of conventional shoulder straps has long been that they tend to cut into the top or peak portion of the shoulders and to otherwise become uncomfortable. In an effort to overcome this disadvantage, it has heretofore been proposed to provide padding for such straps but this expedient has not proved successful.

It is, therefore, an object of my invention to provide a garment supporting shoulder strap which is so constructed that it will not cut into the shoulder of the wearer or otherwise produce the discomfort of conventional straps.

It is a further and more particular object to provide a garment supporting shoulder strap which incorporates novel means for so distributing the weight of the supported garment as to eliminate discomfort.

Another object is to provide a strap which is so constructed that during various body and shoulder movements of the wearer, such as momentarily lowering of a shoulder, the supporting strap may be caused to momentarily lift from engagement with the shoulder and expose the skin beneath the strap to atmosphere.

A still further object of my invention is to provide a garment supporting shoulder strap which is so constructed that it is ventilated.

Other objects will appear hereinafter.

Without intending thereby to limit the broader scope of my invention, except as may appear from the appended claims, I shall now describe a presently preferred embodiment thereof, for which purpose I shall refer to the accompanying drawings wherein:

Fig. 1 is a perspective view showing a garment supported by my improved shoulder straps;

Fig. 2 is an enlarged perspective view of one of the shoulder straps;

Fig. 3 is an enlarged section taken on line 3—3 of Fig. 2;

Fig. 4 is a sectional view showing a modification of my invention; and

Fig. 5 is a sectional view of a further modification.

Referring now to the drawings, I show a pair of my improved straps, each being generally denoted by the numeral 5, and being of the same construction, the straps being shown as being used to support an otherwise conventional brassiere garment B; it being understood, of course, that the straps can be used to support other garments.

Each of the straps comprises a strip 15 of flexible fabric, preferably of a cloth fabric, folded to provide two sleeve-like portions, and in each of the sleeve-like portions there is mounted a reinforcing member 30, although the reinforcing member preferably does not extend throughout the entire length of the strap but only ex-

2

tends throughout that portion which extends over the top or peak of the shoulder. In other words, as shown in Fig. 2, the reinforcing only extends between the points marked x.

5 By reference to Fig. 3, it will be seen that each of the shoulder straps 5 comprises the flexible fabric member 15, consisting of a strip of cloth fabric folded upon itself from each side to provide a bottom wall 40, side walls 41, and top wall portions 42, whose contiguous edges 42a 10 are preferably transversely spaced apart. Thus two outer sleeve-like portions are formed. In each of the sleeve-like portions, or between each of the top wall portions 42 and the underlying portion of the bottom wall 40 I sandwich a reinforcing member 30 comprising a strip of flexible fabric, also preferably a cloth fabric, folded upon itself to provide bottom wall 50, side wall 51, and top wall 52 which top and bottom walls terminate at their sides in attaching flanges 54. A thin strip 55 of relatively hard, pliant material is enclosed within 20 the fold. It is my preference that the strip 55 be of copper and be from two to four thousandths of an inch in thickness.

In some cases, the inner sleeves, comprising walls 50, 25 51 and 52, may be eliminated and the strip 55 enclosed directly within the respective outer sleeve-like portions.

The edge portions 42a of the outer sleeve are secured to the bottom wall 40, the edge portions 42a are secured together, and the flange portions 54 of the reinforcing member 30 are secured in the outer sleeve by fagoted 30 stitching 60 so as to provide between the edges 42a a ventilation space 65 separated from the skin of the wearer only by the underlying portion of the bottom wall 40 of the outer sleeve.

In conventional manner, each of these straps may be 35 made adjustable as to length by means of a conventional buckle 70.

In use, the reinforcing members 30 cause the weight of the supported garment to be evenly distributed over the shoulder of the wearer and whenever the weight is 40 momentarily relieved, as by the wearer lowering a shoulder, the reinforcing causes the pressure of the strap over the shoulder to be momentarily relieved throughout the length of that portion of the strap which carries the reinforcing members.

45 In Fig. 4, I show a modified form of my invention wherein the stiff pliant strip 55a, which is like previously described strip 55, is enclosed within a cloth fabric sleeve 71.

In Fig. 5, I show a further modification wherein each 50 strap 30 is composed of two separate opposed flexible fabric sleeves 80, 81 each having an attaching flange 82. A hard, pliant strip 55b, as of copper, is disposed in each sleeve, and the flanges are secured together in edge to edge abutment by stitching 83.

55 In the form of Figs. 1—3 as well as in the form of Figs. 4 and 5 the hard, pliant strip 55, 55a or 55b is preferably bonded to the enclosing fabric sleeve by a suitable adhesive.

In use, I have found that a person can wear my improved straps to support a garment of considerable weight without the straps causing any of the substantial discomfort heretofore experienced with conventional straps or even with the padded straps heretofore tried. Being 60 pliant, the user can easily pre-shape the strap to conform to the shoulder.

I claim:

1. A supporting strap for a foundation garment comprising a flexible, flattened, tube-like fabric strip, a core element disposed longitudinally in said strip, said core element comprising a length of flat pliant copper disposed longitudinally in and secured to said strip and

adapted to cause said strip to conform to and remain in conformance with the shoulder of a wearer, and means for securing the ends of said strip to a garment.

2. A supporting strap for a foundation garment comprising a flexible, flattened tube-like fabric strip, a core element disposed longitudinally in said strip, said core element comprising a pair of parallel sleeve-like flexible fabric strips, a flat length of pliant metal disposed longitudinally in and adhered to each of said sleeve-like fabric strips and adapted to cause said strips to conform to and remain in conformance with the shape of the shoulder of a wearer, stitching means securing said sleeve-like strips to said tube-like strip, and means for securing the ends of said tube-like strip to said garment.
